JESSE W. BARNES AND THOMAS C. REYNOLDS, OF ONEONTA, NEW YORK.

SPARK PLUG.

Application filed May 21, 1925. Serial No. 31,871.

To all whom it may concern:

Be it known that we, JESSE W. BARNES and THOMAS C. REYNOLDS, citizens of the United States, residing at Oneonta, in the county of Otsego and State of New York, have invented certain new and useful Improvements in Spark Plugs, of which the following is a specification.

This invention relates to spark plugs and has for its object to provide, in a manner as hereinafter set forth, a plug of such class, having means whereby a series of intensified sparks are produced to insure proper ignition and explosion of the explosive mixture supplied to the combustion chamber of an internal combustion engine.

A further object of the invention is to provide, in a manner as hereinafter set forth, a spark plug with means to form a plurality of sparking points capable of producing what may be termed a multiple spark, thereby insuring a more perfect explosion of the gases and increasing the power produced as the result thereof in the sense that as the explosion is more perfect, less gas is consumed, and the engine more easily cleaned, thereby increasing its efficiency.

A further object of the invention is to provide, in a manner as hereinafter set forth, a spark plug provided with a combustion chamber, so arranged with respect to the means for producing multiple sparks whereby when ignition takes place the gas in the plug will blow past said means to clean off any accumulation of carbon or other fouling substances, under such conditions keeping the said means always clean and overcoming fouling of the plug.

Further objects of the invention are to provide, in a manner as hereinafter set forth, a spark plug for the purpose referred to, which is simple in its construction and arrangement, strong, durable, thoroughly efficient in its use, readily assembled, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifi-

cations can be resorted to which come within the scope of the claims hereunto appended.

In the drawings wherein like reference characters denote corresponding parts throughout the several views:—

Figure 1 is a vertical sectional view of a spark plug, in accordance with this invention.

Figure 2 is an inner end view thereof.

Figure 3 is a section on line 3—3, Figure 1.

Referring to the drawings in detail, 1 denotes a metallic shell, 2 a porcelain plug body having embedded therein and extended therefrom a central electrode 3, and 4 indicates a packing gland for detachably connecting the plug body 2 to the shell 1. 70 Interposed between the plug body 2 and the shell 1, intermediate the ends of said plug and shell, is a gasket 5, which seats on a shoulder 6 arranged on the inner face of the shell 1, and said gasket is engaged by the plug body 2 when the latter is coupled in operative position within the shell 1 by the gland 4. The foregoing elements are of known construction with the exception that the inner face of the shell 1, at the inner terminal portion thereof is provided with threads 7.

Threadedly engaging with the inner end of the shell 1, as well as projecting therefrom, is a carrier formed of insulation, such as porcelain, and which is referred to generally by the reference character 8. The carrier consists of a hollow cylindrical body having one half of greater outer diameter than the other and that portion of smaller outer diameter is indicated at 9 and the portion of greater outer diameter is indicated at 10. The forming of the body of the carrier 8 of two different outer diameters provides an annular peripheral shoulder 11, 95 which when the carrier is mounted in position with respect to the inner end of the shell 1 abuts against the inner end edge of the shell. The periphery of the portion 9 of the carrier 8 is threaded for engagement with the threads 7 of the shell 1, whereby the carrier is detachably secured to the inner end of the latter and when in operative position the shoulder 11 abuts against the inner end of said shell.

The inner face of the carrier 8 is so formed to gradually flare in opposite directions from the transverse center of the car-

rier, as indicated at 12, 13. The flare of the portion 13 is greater than the flare of the portion 12. That end of the carrier 8, arranged within the shell 1, in connection with 5 the enlarged intermediate portion of the plug body 2, provides a combustion chamber 14 and the oppositely flared opening formed by the carrier constitutes what may be termed a passage for said chamber to permit 10 of the entrance and discharge of a portion of the explosive mixture.

Embedded in the carrier 8 is a ground electrode 15 which extends across the opening in the carrier at the outer end thereof 15 and which also is exposed at the shoulder 11 so as to have electrical contact with the inner end edge of the shell 1. The portion of the electrode 15 which extends across the opening at the outer end of the carrier 8 is indicated 20 at 16. Embedded in the carrier 8 and extending across the opening at the outer end of the latter is a series of auxiliary electrodes 17, 18, 19 and 20. The portions of the electrodes 17, 18, 19 and 20 which extend 25 across the outer end of the opening or passage formed in the carrier 8, are indicated at 21, 22, 23 and 24 respectively. The electrode 21 is extended through the carrier 8 for a portion of its length and extends into the 30 opening or passage formed by the carrier 8, intermediate the ends thereof, as at 25, and preferably to a point in close proximity to the inner end of the electrode 3, but if desired, the electrode 21 can contact with the 35 inner end of the electrode 3. The electrodes 15, 17, 18, 19 and 20 are independent of each other and further are spaced substantially equi-distant with respect to each other. The portion 21 of the electrode 17, in connection 40 with the portion 22 of the electrode 18 provides a spark gap, the portion 22 of the electrode 18, in connection with the portion 23 of the electrode 19 provides a spark gap, the portion 23 of the electrode 19, in connection 45 with the portion 24 of the electrode 20 provides a spark gap, and the portion 24 of the electrode 20, in connection with the portion 16 of the electrode 15 provides a spark gap.

50 The providing of the plug with the combustion chamber allows the plug to clean itself and prevents fouling of the portions of the electrodes which extend across the outer end of the carrier 8 when each explosion takes place. The passage to the combustion chamber is restricted, which increases the ability at the time of the explosion to clean the plug and to prevent fouling of the auxiliary electrodes. When the explosive mixture is supplied to the engine cylinder a portion thereof will pass the electrodes 15, 17, 18, 19 and 20 and enter the combustion chamber 14. When ignition takes place the portion of the mixture in the combustion chamber will blow past the elec-

trodes mentioned and clean off any accumulation of carbon or other fouling substance. The shape of the passage to the combustion chamber is such as to prevent any accumulation of oil thereon as it will drip off.

70 The auxiliary electrodes are so arranged that the spark will jump successively from one to the other and then to the ground electrode and which will intensify the sparks, under such conditions the plug provides for greater ignitability over the ordinary plug now in general use. The construction as shown provides for a spark at each gap at the inner end of the plug, thereby making a series of sparks, each of which is far more intense than the ordinary single spark because of the various spark gaps or resistance spaces which set up a resistance at the circuit and intensify the ignitability. By increasing the heat of the spark as well as the number of sparks, the explosive mixture ignites quicker and more effectively than in the form of plug now in general use, and under such conditions an engine can be operated with a leaner explosive mixture than that when a plug with a single spark is employed.

75 It is thought that the many advantages of a spark plug, in accordance with this invention, can be readily understood, and although the preferred embodiment of the invention is as illustrated and described, yet it is to be understood that changes in the details of construction can be had which will fall within the scope of the invention 80 as claimed.

85 What we claim is:—

1. A spark plug comprising a hollow carrier adapted to be connected to and within and further project from the inner end 90 of the shell of the plug, said carrier forming a passage for the reception of the inner terminal portion of the central electrode of the plug and provided with a series of opposed, spaced electrodes extending across the inner end of said passage, one of said electrodes extending partly through one side of the body of the carrier lengthwise thereof and projecting into said passage, intermediate its ends, to a point in close proximity to the inner end of the central electrode of the plug, and associated therewith, and another of said electrodes extending partly through the other side of said body of the carrier lengthwise thereof and having an exposed terminal for contact with the inner end edge of the shell of the plug.

105 2. A spark plug comprising a hollow carrier provided with a peripherally threaded 110 reduced portion forming a peripheral shoulder, said reduced portion adapted to have threaded engagement with the inner face at the inner terminal portion of the shell of the plug to secure the carrier to the shell and 115 to provide for the abutting of the shoulder 120

- against the inner end edge of the shell, said carrier forming a passage for the reception of the inner terminal portion of the central electrode of the plug and provided with a series of opposed, spaced electrodes extending transversely across the inner end of said passage; one of said electrodes having an extension extending partly through one side of the body of the carrier lengthwise thereof and projecting into said opening, intermediate its ends, to a point in close proximity to the inner end of the central electrode of the plug and associated therewith and another of said electrodes of said series having an extension extending partly through the other side of the body of the carrier lengthwise thereof and having an exposed terminal at said shoulder in contact with the inner end edge of the shell of the plug.
3. A spark plug comprising a peripherally shouldered hollow carrier adapted to extend into, be secured directly within and project from the inner end of the shell of the plug and further having its shoulder abutting against the inner end edge of said shell, said carrier forming a passage into which is adapted to extend the central electrode of the plug, a series of spaced opposed electrodes extending across the inner end of said passage, one of said electrodes having a terminal thereof exposed at said shoulder for direct contact with the inner end edge of the shell and another of said electrodes having a terminal portion thereof projecting through the wall of and into said passage and associated with the inner end of the central electrode of the plug.
4. A spark plug comprising a hollow carrier adapted to be secured directly within and project from the inner end of the shell of the plug, said carrier forming a passage for the reception of the inner end terminal portion of the central electrode of the plug; a series of opposed, spaced electrodes extending transversely across the free end of said carrier, the inner electrodes of said series having their ends embedded in the free end edge of the carriers, each outer electrode of said series provided with an extension, one end of each of said outer electrodes embedded in the free end edge of said carrier, one of said extensions extending partly through one side of said carrier and projecting through the wall of and into said passage and associated with the inner end of the central electrode of the plug, the other of said extensions extending lengthwise through a part of the other side of said carrier and exposed at the periphery of the latter for contact with the inner end edge of the shell of the plug.

In testimony whereof we affix our signatures hereto.

JESSE W. BARNES.
THOMAS C. REYNOLDS.
